UNITED STATES PATENT OFFICE.

RICHARD V. RUSSELL, OF ROCHESTER, MINNESOTA.

COMBINATION-CASE FOR BARBERS.

SPECIFICATION forming part of Letters Patent No. 471,752, dated March 29, 1892.

Application filed June 25, 1891. Serial No. 397,454. (No model.)

To all whom it may concern:

Be it known that I, RICHARD V. RUSSELL, of Rochester, in the county of Olmstead and State of Minnesota, have invented a new and useful Improvement in Combination Cases for Barbers, of which the following is a description, reference being had to the accompanying drawings, which are a part of this specification.

10 The object of my invention is to provide a combination-case adapted for holding the tools and supplies of a barber in a convenient and satisfactory manner, which case is so formed and constructed as not to catch and 15 retain refuse or foreign matter in inaccessible places and is readily cleaned.

Figure 1 is a top plan view of the complete case, a single implement being indicated in dotted lines. Fig. 2 is a side elevation of the 20 case. Fig. 3 is an end view of the case, looking at it from the right, as shown in Fig. 2, a razor held in the case being indicated in dotted lines. Fig. 4 is a transverse section of the case on line 4-4 of Fig. 2, a pair of shears 25 held in the case being indicated in dotted lines.

The base or pedestal A is of elongated form, and is constructed of any suitable material, preferably of wood. The upright receptacle B is fixed on the pedestal A near one end 30 thereof, is preferably made of wood, and is provided with a series of vertical sockets C, D, and E, of suitable form in cross-section and in height to adapt them to receive and hold 35 removably therein implements or tools as follows: The sockets C are adapted to hold razors F, the sockets D to hold combs, and the sockets E to hold shears G. The sockets E are tapered inwardly on two opposite sides near their lower ends at E', whereby they are 40 adapted to receive and support the shears near their tapering points, securing the blades tightly together. The receptacle B is provided in its lower edge with an inverted channel H, which intersects the several sockets C, 45 D, and E and permits any refuse or foreign matter that may adhere to the tools, and thereby get into the sockets to fall upon the pedestal and to be readily removed therefrom through the channel. That portion of the 50 top of the receptacle B about the socket E is preferably faced with sole-leather I, through which apertures are formed corresponding

with the sockets, though a little less in size than the sockets are in cross-section, so that the leather projects inwardly slightly beyond 55 the walls of the sockets, thereby forming a cushion against which the shears are received. Along the sides of the other end of the pedestal there are upwardly-projecting flanges K, formed integrally with the pedestal or in the 60 nature of side rails secured rigidly thereto, forming a shallow channel between them of sufficient width and depth to receive therein the heads of clippers L. These clippers are held in place and their knives are protected 65 by cross-bars M, secured to the flanges or side rails K, and under which the knives of the clippers are removably inserted. Along the entire front of the pedestal and projecting laterally therefrom is a wire rack N, secured 70 rigidly thereto and provided at or near its outer edge with short supporting-legs O. The rack is preferably curved or hollowed in laterally, as seen at P, whereby it is better fitted and adapted for holding thereon brushes, 75 sticks of cosmetic, and similar articles.

From the foregoing description and reference to articles that may be supported and held thereon the use of the device will be 80 fully understood.

What I claim as new, and desire to secure by Letters Patent, is—

1. A barber's case comprising a horizontal elongated pedestal adapted to stand on a suitable support, an upright receptacle rigid 85 on and above the pedestal, having a series of vertical sockets entering the receptacle at its top, which sockets are inclosed at the sides and are adapted to receive barbers' implements therein and hold them vertically projecting partially above the case, a horizontal shallow channel adjoining the upright receptacle, formed by parallel flanges extending upwardly at the sides of the pedestal, cross-bars fixed to the flanges over the channel, under 90 which in the channel clippers may be inserted and held, and a rack fixed to one edge of the pedestal and projecting laterally therefrom, substantially as described.

2. In a barber's case, a horizontal elongated 100 pedestal adapted to stand on a suitable support, a receptacle rigid to and extending upwardly from and above the pedestal, a series of vertical sockets entering the receptacle at

its top, which sockets are adapted to receive and hold barbers' shears, razors, and similar implements vertically therein and projecting upwardly therefrom, and a channel in and extending through the base of the receptacle, longitudinally intercepting the vertical sockets at their lower ends and adapted to permit of the removal therefrom of refuse from the sockets, combined substantially as described.

3. In a barber's case, an upright receptacle above a pedestal and therein vertical sockets entering the receptacle at its top, which sockets are each of suitable size to receive therein the closed blades of a pair of shears, the opposite walls of the socket being substantially parallel from the top of the receptacle for a considerable distance downwardly to near its bottom and thence tapering inwardly on two opposite sides, the tapering walls being adapted to receive the bearing of the tapering ends of the blades of the shears and by the gravity of the shears to hold the blades tightly closed on each other, and a cushion of leather or its

equivalent about the socket, at its mouth 25 adapted to receive and bear yieldingly against the outer longitudinal edges or backs of the blades of the shears, combined substantially as described.

4. In a barber's case, the combination, with 30 an upright implement-holding receptacle, of an elongated pedestal on which the receptacle is supported, a clipper - holding device formed on the pedestal, including parallel flanges projecting upwardly at and from the 35 sides of the pedestal, forming a shallow channel on the pedestal, and cross-bars secured to the flanges above and transversely of the channel at suitable distances from each other and from the pedestal to receive thereunder 40 and hold the heads of pairs of clippers, substantially as described.

In testimony whereof I affix my signature in presence of two witnesses.

RICHARD V. RUSSELL.
